UNITED STATES PATENT OFFICE

WALTER M. CROSS, OF KANSAS CITY, MISSOURI, ASSIGNOR, BY MESNE ASSIGNMENTS, TO GASOLINE PRODUCTS COMPANY, INC., OF WILMINGTON, DELAWARE, A CORPORATION OF DELAWARE

APPARATUS FOR DEPHLEGMATING VAPORS

Application filed October 29, 1923. Serial No. 671,356.

This invention relates to improvements in an apparatus for dephlegmating vapors and refers more particularly to dephlegmating means adapted to be used in partially condensing, dephlegmating or refluxing high boiling point oil fractions from the lighter vapors.

Among the objects of the invention are to provide a construction in which the vapors are introduced and continuously permitted to rise through an apparatus containing a plurality of pools vertically arranged one above the other in a manner whereby the vapors are caused to percolate through the liquid maintained in the separate pools; to provide a construction in which the oil, after being subjected to a dephlegmating action, or being percolated through the pools of oil, is further refluxed by being brought in contact with elements through which a cooling medium is passed and coming in radiating contact therewith, has separated out further of the relatively high boiling point fractions; to provide a construction in which the condensate separated out is gravitated into the bottom of the apparatus where it is subjected to relatively high temperature in order to prevent absorption of the hydrocarbons of different character, and revaporization of any lighter fractions which are returned; to provide a construction which permits of regulation within relatively narrow limits, whereby vapors may be treated and condensates of a predetermined character separated out; and, in general, to provide a construction of the character referred to.

In the drawings,

Fig. 1 is a sectional view taken through the center of the apparatus, showing the interior construction.

Fig. 2 is an enlarged detail of one of the cap elements.

Fig. 3 is a view taken along the line 3—3 in Fig. 1.

In the drawing, is shown only a dephlegmating column. It is understood, however, that this unit is connected up with a still, or conversion apparatus, whereby liquid materials, particularly hydrocarbon products, are

treated either under atmospheric or super-atmospheric pressure.

Referring in detail to the drawing, the apparatus consists principally of a shell 1, which is preferably cylindrical although other shapes may be used. The vapors are introduced to the shell through the vapor line 2 controlled by a valve 3, and after treatment, are withdrawn from the top of the column through the line 4. A draw-off line 5 is tapped into the bottom of the column, supplying a means for withdrawing the unvaporized liquids collecting therein. This draw-off line is controlled automatically by a liquid level regulating device diagrammatically shown at 6, 65 which controls the valve 7 in the draw-off line. In the bottom portion of the column is a reboiler, or reboiling header, consisting of headers 8 and 9, connected by pipes 10, which extend diametrically across the column. 70 The header 8 is affixed to the shell, while the header 9 is a floating construction to permit unequal expansion and contraction. As clearly shown in the drawings, header 8 is mounted on the exterior of the shell 1. Also, the box or mounting 9' for the sliding or floating header 9 is positioned on the exterior of the shell 1. At this point it should be noted that the floating header 9 is positioned entirely within the box 9'. This construction is advantageous in 75 that it provides a larger surface of contact between the heating tubes 10 and the liquid to be reboiled, that is, the length of the heating tubes are substantially equal to the exterior diameter of the shell 1. The heating medium, which usually takes the form of a highly heated oil, although steam or other fluids may be utilized, is introduced through the pipe 11 to the upper compartment of the header 8, and directed thence through the upper pipes across to the header 9 and back through the lower pipes to the lower compartment of the header 8 and out through the line 12. Centrally of the column are positioned a plurality of partitions, or pans, 13, which are 80 perforated and have short vertical risers 14 set therein. These risers furnish communication between the separate compartments, or between the separate pans, and permit the vapors from below to rise into the compartment 85 100

ment above. These risers are capped, as shown at 15, by cup-shaped elements which have serrated lower edges. The vapors, on being introduced through the line 2, pass up through the several risers in the pans and are caused to percolate through pools of oil maintained on the pans by the vertical down-comers or stand-pipes 16, into which the excess liquid overflows into the next pan below. 5 These stand-pipes are open-ended, their upper edges controlling the level of the liquid in the separate pans, and their lower ends being immersed in the pool below, thus assuring a liquid seal and preventing the vapors working back through these standpipes. The vapors passing up through the risers are directed downward over the lips of the risers by the caps 15, and percolated out through the serrated edges of the caps through the oil pool, and thence up through the next set of risers to the pool above. In this manner, the vapors are subjected to the scrubbing action, which extracts and eliminates, to a considerable extent, the high boiling point fractions 10 as the pools of oil become progressively cooler near the top. On being percolated through the upper pool, the vapors bubble through the liquid and are caused to pass the coils 17 and 18 through which cooling mediums are passed. 15 Cool oil, water, or any other liquid medium, may be utilized for taking up further heat from the vapors and separating out additional high boiling point fractions. This temperature of the vapors may be controlled 20 as desired to permit vapors of the proper characteristics to pass over from the top of the column through the line 4 for final condensation. 25

It is understood that, while normally the 40 material to be treated will be introduced to the column in vapor form, under certain circumstances the vapors prior to their introduction to the dephlegmating column may be partially condensed and arrive in a fluid 45 form, or, part vapor and part liquid. Under such circumstances, the liquid will gravitate immediately to the lower pool where it will be subjected to the heat of the reboiler and treated for the extraction of any volatile products remaining. 50

Dephlegmation, or partial condensation of the character described, for the removal or separation of high boiling point fractions from vapors, is well-known and old in the art 55 of distillation. Further, to maintain a series of pools, one above the other, and percolate the vapors therethrough to remove undesirable cuts or fractions, is commonly known and a practice which is generally utilized for this 60 purpose. There are, however, few efficient towers for this purpose.

As a result of careful experimentation and trial, it has been found that proper dephlegmation or refluxing takes place under certain 65 relatively limited conditions. These ele-

ments, or factors, may be accurately ascertained, and comprise the novelty of the present invention; that is, by controlling certain elements, or factors, within narrow limits a definite and efficient result may be obtained in the dephlegmation of vapors, while, if this relation is departed from to any considerable extent, the results are problematic and the outcome usually highly inefficient. 70

The elements, or factors, which control 75 efficient operation, are the velocity which depends upon the differential pressures maintained in the upper and lower portions of the apparatus, secondly, there is a definite and limited relation between the area of the surface of the pools through which the vapors pass and the size of the orifices, risers, or pipes through which the vapors pass from one pool to the next. A further determining factor in the velocity of the vapors in their 80 travel through the column, is the rate of input which may be carefully controlled by the valve 3 and the pipe 2; thus, it is undesirable to introduce the vapors at a rate in excess of that by which they can be handled 85 in the risers. Otherwise, they will tend to work up through the down comer pipes and blow the entrained material or liquid over the top of the column with the treated vapors. 90

A further disadvantage in permitting the 95 vapors to travel at too high a velocity is their tendency to break the liquid seal maintained by the down-comer pipes between the respective pans or pools of oil on the pans.

It has been found that where the vapors 100 travel at from three to eight feet per second, the proper selective absorption is effected. An optimum speed of approximately four and one-half feet per second has been utilized with considerable success. Where the speed 105 is increased above this, it is desirable to increase the distance between the pans,—thereby reducing the possibility of disrupting the liquid seals. The dimension of a tower, which has given satisfactory results, are substantially as follows: 50 feet high, 7 feet 3 inches diameter, with thirty pans positioned centrally of the tower, the risers being approximately four inches in diameter. It is understood, of course, that these dimensions may be 110 varied according to the amount of vapors to be treated,—the dimensions being included merely to disclose a satisfactory construction 115 commercially operated.

A further factor of importance in the 120 selective absorption of the fractions is the relation between the area of the pans or pools maintained on the pans and the ports or risers through which the vapors travel progressively from one pool to the next above. 125 If the area of the ports is in relation to substantially one-fifth of the area of the pools, conditions will be such as to produce what has been found to be the most satisfactory treatment. 130

A difference in pressure, between the upper and lower portions of the column, of from fifty to eighty inches of water-measured pressure has been found to be the most satisfactory and produce a rate of velocity of the vapors giving the most satisfactory and efficient results in the selective absorption of the higher boiling point products.

In addition to the factors mentioned, the shape of the slots cut in the lower edges of the riser caps has been found to have considerable effect in the achieving of satisfactory separation of the objectionable oil fractions. These serrations, or slots, have preferably the form of a truncated triangle.

The construction has been successfully utilized in making endpoint gasoline, by controlling the velocity of the vapors within the limits mentioned and passing them through a construction having the area of the risers and pools substantially within the relation mentioned. The higher boiling point fractions may be satisfactorily eliminated and an endpoint gasoline distillate produced.

As illustrative of the manner in which the vapors are treated, a kerosene distillate of approximately 42.1° Baumé having an initial boiling point of 330° F. and an endpoint or dry distillate temperature of 534° F., was obtained by ordinary distillation. This distillate was then redistilled and the vapors passed through a fractionating tower such as that hereinbefore described. From this kerosene there was obtained 60% of distillate within the boiling range of gasoline, or 437° F.

When 39.5° Baumé North Texas crude oil was distilled, 10% more gasoline was obtained from it than by distillation with the ordinary fractionating tower. It is understood, of course, that the vapors, passing over from the top of the dephlegmating column, are directed to a condensing means and thence to a collecting tank or storage where the gasoline-like distillate is accumulated.

I claim as my invention:

1. An apparatus for treating hydrocarbon vapors comprising a tower, a plurality of horizontal pans positioned in said tower, one above the other, each adapted to support a pool of liquid, liquid sealed risers associated with each of said pans, liquid downcomer pipes associated with the pans and positioned relative to the pans to convey excess liquid from one pan to beneath the surface of liquid in the pan just below, said tower having a vapor inlet port adjacent the lowermost pan and an outlet port at the top thereof, means for maintaining a body of reflux condensate in the lower portion of said tower, an outwardly projecting header box in the side of said tower below the liquid level, a reboiling element positioned within said tower beneath the liquid level, said reboiling element consisting of a plurality of tubes ex-

tending between headers, one of said headers being fixed to the exterior of said tower opposite said box, and the other header being slidably mounted entirely in said box, to permit expansion of the reboiling elements independently of the tower.

2. An apparatus for refluxing hydrocarbon vapors comprising a tower having inlet and outlet ports, a plurality of horizontal pans arranged within said tower, one above the other, adapted to support liquid pools, liquid sealed risers and liquid downcomer pipes associated with the pans adapted to permit vapors to rise and liquid to gravitate between the successive pans, means for maintaining a liquid level in the lower portion of said tower, an outwardly extending box mounted on the exterior of the shell of said tower below the liquid level, a reboiling element positioned within the lower portion of said tower, said reboiling element consisting of a plurality of tubes extending between headers, one of the headers for said element being mounted exteriorly of the tower opposite said box, the other header for said element being floatingly mounted within said box, and being positioned within the box so as to extend on the outside of the inner surface of the shell.
